United States Patent Office.

NAPOLEON MAISONNEUVE, OF KANKAKEE, ILLINOIS.

Letters Patent No. 90,008, dated May 11, 1869.

IMPROVEMENT IN CORN-PLANTERS.

The Schedule referred to in these Letters Patent and making part of the same.

To all whom it may concern:

Be it known that I, NAPOLEON MAISONNEUVE, of Kankakee, in the county of Kankakee, and State of Illinois, have invented certain new and useful Improvements in "Corn-Planters," and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

Figure 1 represents the side elevation, and

Figure 2, the plan of the machine.

Figure 3 represents a section of the hopper and conveying-tube.

The nature of my invention consists in a device to operate the dropper and the marker, and so arranged that the grain is dropped with every revolution of the covering-wheels, the marker stirring the earth every time the corn drops, and thus showing to the driver the regularity or irregularity of the cross-lines of the hills.

It consists, also, in stationary brushes, placed inside of the hoppers, and above the cells, for the purpose of brushing off the surplus of grain, and leaving in the cells only the necessary number of kernels required.

A is the frame.

B is the axle, to which covering-wheels C C, and cog-wheel D are secured.

E is a pinion, to the shaft of which, d, journalled to the frame, cam F is secured.

The cam is provided with roller f, at the end, for the purpose of diminishing the friction produced by the operation of the cam on the end of lever N.

The machine is put in or out of gear by the cog-wheel K, set on shaft G, working on a pivot at one end, and having a side motion at the other end, which end is operated by the hand-lever I, connected with it by means of rods i i, and plate H, pivoted to the frame at h.

By this contrivance, cog-wheel K can be brought in contact both with cog-wheel D and pinion E.

Beam M is journalled to the frame A, and is firmly connected with arms m m, jointed to the valves, or slides n n, containing the cells, and working in the conveying-tubes of the hoppers S S.

The beam is also firmly connected with a long and slightly-curved lever, or arm, N, the end of which is shaped into an inclined plane, of sufficient surface to permit the roller d of cam F to operate upon and to depress this end sufficiently.

By the operation of cam F on lever N, beam M operates the slides n n, and drops the corn.

The beam M is also provided with two short horizontal arms, O O', one of which, O, is pressing against spring P, as the beam partially revolves, which spring brings the beam and the slides n n back into their former position.

The other arm O' is jointed to a marker, Q, which, being pressed against the ground, makes a mark every time the corn drops, which marks show to the driver whether the hills are planted regularly, and form perfect rows crossways.

The marker is provided with a loop on its front side, through which passes the loose end of the spring q, secured to the frame, which spring brings the marker into its vertical position every time it is raised from the ground.

A stationary brush, R, is placed in the hopper S above the slide, and is secured to the front side of the hopper, and has a purpose of brushing off the surplus kernels filling the cell r, made to contain only a certain number of kernels, when the slide n is being operated by the beam M.

Draught-pole T, provided with pulley t, is secured firmly to the beam U, hinged to the frame A, and passes between standards V, provided with holes v v, through which a pin is passed above the tongue, at any desirable height, so as to force the runners W W deeper or shallower into the ground.

Treadle X, at its front end, is hinged to the front end of the frame A, and a rope, Y, secured to it at y, passes over pulley t, and has its other end secured to the frame A, at Z.

By this arrangement the driver can lift up the front part of the machine above the ground, when turning the machine around, or taking it to the place of work.

Having thus fully described my machine—

What I claim as new, and my invention, and desire to secure by Letters Patent, is—

1. The combined arrangement of the beam M, lever N, arms m m and O O', and marker Q, all arranged and operating substantially as herein described, and for the purpose specified.

2. The arrangement of the tongue T, pivoted to the upper side of the frame A, passing between the uprights V and the foot-lever X and cord Y, all as herein shown and described.

NAPOLEON ^{his} X MAISONNEUVE.
mark.
